CLAIM

An ornamental design for a dual dispensing napkin holder, as shown and described.

DESCRIPTION

FIG. 1 is a perspective view of a dual dispensing napkin holder showing our new design;

FIG. 2 is a front view thereof;

FIG. 3 is a rear view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective of a blank used to construct the dual dispensing napkin holder of FIG. 1;

FIG. 9 is a top plan view thereof;

FIG. 10 is a front view thereof;

FIG. 11 is a rear view thereof;

FIG. 12 is a left side view thereof; and,

FIG. 13 is a right side view thereof.

The broken lines and surface shading shown in the figures are for illustrative environmental purposes only and form no part of the claimed design.
